(57) **CLAIM**

The ornamental design for a table, as shown and described.

DESCRIPTION

FIG. 1 is a perspective view of a table;

FIG. 2 is a top plan view thereof;

FIG. 3 is a bottom plan view thereof; and,

FIG. 4 is a right side elevation view thereof, which is identical to the left side elevation view thereof.

The broken lines represent portions of the structure that forms no part of the claim.
